UNITED STATES PATENT OFFICE.

A. INGRAM PARSONS, OF ST. LOUIS, MISSOURI; H. F. PARSONS (ADMINISTRATOR OF SAID A. INGRAM PARSONS, DECEASED) ASSIGNOR, BY MESNE ASSIGNMENTS, TO THE PARSONS BLOCK, SWITCH AND FROG COMPANY, OF NEW YORK, N. Y.

AUTOMATIC RAILWAY-SWITCH.

SPECIFICATION forming part of Letters Patent No. 396,418, dated January 22, 1889.

Application filed March 11, 1886. Renewed October 4, 1888. Serial No. 287,259. (No model.)

To all whom it may concern:

Be it known that I, A. INGRAM PARSONS, a citizen of the United States, residing at St. Louis, in the county of St. Louis and State of 5 Missouri, have invented certain new and useful Improvements in Railway-Switches, of which the following is a full, clear, and exact description.

This invention relates to switch mechanism 10 for railways, to be operated by the engineer from his cab on a moving train.

The invention, briefly stated, comprises, as an essential element, a switch-lever that stands locked and is connected by rods to a 15 series of operating-levers, which are actuated by an approaching train to place the switch in the desired position, and by the same train as it recedes or passes to restore the switch to its normal position, all as I will now proceed to set forth and claim.

In the accompanying drawings, in the several figures of which like parts are similarly designated, Figure 1 is a plan of a portion of 25 a main track and siding equipped with my switch. Fig. 2 is a diagrammatic and exaggerated side elevation of the switch-operating mechanism in one position, and Fig. 2^x a similar view in the reverse position. Fig. 3 is a cross-sectional view of an engine-cab 30 and part of my switch mechanism, and Figs. 4, 5, and 6 details to be referred to.

The main track A, siding B, and switch-rails C may be of usual construction and arrangement. The switch-bar *a* is connected to 35 a lever, *b*, which latter is pivoted at *c* in a suitable bracket, *d*, supported in any appropriate manner. The short arm of this lever *b* is made as a segmental worm-gear, *e*, which is engaged by a worm-shaft, *f*, journaled in 40 the bracket *d*. (See details in the plan and elevation, Figs. 4 and 5, respectively.) This worm-shaft, in the example shown, has a crank-arm, *g*, which is connected to an endless rod, chain, cable, or rope, or equivalent 45 medium, *h*; but the connection may be other than a crank-arm—for example, chains connected to drums on the worm-shaft in opposite directions and connected oppositely to

the endless rod—any connector being available which will rotate the shaft in opposite 50 directions by opposite movements of the endless rod. This “endless rod” *h*, so called, may consist of two rods connected at their ends by chains or other flexible mediums passing over pulleys *i i*, whereby said rods are allowed 55 freedom of endwise movement.

Suitable brackets are erected on one or both sides of the track to receive levers *j*, which normally stand up, and which are made with segmental, eccentric, or cam-shaped lower 60 ends, *k*, grooved to receive chains or other flexible mediums, *l*, to connect them to one or the other member of the endless rod *h*. (See details in side and edge views, Fig. 6.) To the rod *h* are connected, by a reversing or 65 double-acting medium, the visual signals *m*, such medium being here shown as two chains, *n*, leading from opposite points on the bar and oppositely wound on drums *o* on the signal-staff, so that the operation of the switch 70 actuates the signals.

A number of switch-levers, *j*, are arranged at each approach to the switch and some distance from it. Some are connected to the endless rod so as to act to set the switch for 75 the siding, and others to set it for the main track, and these levers may be designated by any arbitrary sign, as by different colors or shapes. The operation of one lever of one kind operates all of that kind in the same 80 direction and reverses all those of the other kind, and hence puts them in position to be acted upon to reverse the operation of the other. Thus, if the switch be set for the siding by an approaching train, the proper lever 85 is acted upon—that is to say, it is leveled—while the oppositely-acting levers are raised up.

Now, if it be desired to set the switch for the main track after the train passes to a siding, these last-named levers are in position to be acted upon to effect this object. It will be seen that by proper location of the levers a train can be run from the main track to a siding by its engineer operating the switch from 95 his cab, as will presently appear, and he can

then restore the switch or set it for the main track for another passing train, which last-named train having passed, the switched-off train on the siding can set the track for itself 5 to pass to the main track, and, having so passed, can again set the switch for the main track.

Referring to the diagram, Fig. 2, it will be assumed that a train is about to go from the 10 main track to the siding in the direction of arrow x . Either of the levers 2, 4, or 6 may be engaged to effect the necessary movement of the switch for this purpose. Suppose lever 2 is positively engaged to this end; then 15 it will depress positively the levers 2, 4, and 6, and by slackening the connection of the levers 7 and 10 with the operating medium h permit gravity or a spring to act to cause them to follow. It will be observed that these 20 several levers 2, 4, 6, 7, and 10 positively engage the operating medium h to move it in one direction only, and when thus operated (the dotted arcs designating the direction of movement of each and all of the levers) all 25 the other levers will assume the contrary position—that is to say, the lever 3 will be pulled up, the lever 5 will likewise be pulled up, and so also will the two levers 8 and 9 be positively elevated. This position of parts is indicated 30 in Fig. 2^x. The connections of all the levers with the operating medium h is now positive. The train on the siding or the train following, and which is to pass on the main track, may 35 reset the switch so as to leave a continuous main track. If this be done by the train on the siding, the lever 9 will be operated, and if by the train following, then the lever 5 will be operated, and in either case the levers 3, 40 5, 8, and 9 will all go down, the first, 3, by its slack connection, allowing gravity or a spring to act and in descending take up the slack, 5 by positive movement, and 8 and 9 by gravity, while the levers 2, 4, 6, 7, and 10 will be elevated by positive movement of the operating medium h . This then restores the levers 45 to the position shown in Fig. 2, and provision must be made for getting the switched-off train back on the main track. As the switch mechanism will be duplicated at both ends of 50 the siding, it is obvious the train may be run off ahead; but if it have to back onto the main track from the siding, then the switch may be reversed by operating lever 7, and again reversed to open the main track by 55 backing on the lever 3.

In every operation of the switch the parts are positively held and locked by the worm-gearing.

A safety-lever, p , is arranged on the side of 60 the track opposite the levers j and connected by a rod or shaft, q , to one of such levers, j , to operate to always set the switch for the main track. This safety-lever will be located some distance from the switch, so that at 65 night or in fogs the engineer may operate this lever and rest assured that he is all right

as to the switch. The rod-operating levers are so connected with it that they act upon it in one direction only, and if depressed in the opposite direction they are ineffectual, as will 70 readily appear.

The means for operating the switch-levers consists of a horizontal bar, r , suitably suspended beneath the engineer's cab and provided with an operating-lever, s , pivoted in 75 the cab, and having a treadle, t , or hand-lever u , or both, for operating it to throw it out laterally either side of the track to engage the levers, as clearly shown in Fig. 3.

The levers, rods, and worm-gearing may be 80 boxed in or otherwise suitably secured from damage or tampering.

A hand-lever, v , Fig. 5, may be employed for operating the switch manually.

I have thus set forth one simple and efficient means of practicing my invention. Obviously the details are susceptible of variation.

What I claim is—

1. A railway-switch comprising a switch-bar, a worm-geared operating-lever, a worm-shaft meshing therewith, all arranged at the side of the track, an endless bar, chain, cable, or the like, and vertical levers connected thereto to move it in opposite directions, and 95 means, substantially as described, for actuating said vertical levers to rotate said worm-shaft, and thereby actuate the worm-geared lever and simultaneously lock it, and consequently the switch, in desired position, substantially as set forth.

2. A railway-switch-operating mechanism comprising an endless rod, chain, cable, rope, or the like, mounted upon pulleys, a series of vertical levers to move said rod in either of 105 two directions, and a switch-lever having a worm-gear, and a worm-shaft connected to said rod, and all arranged at the side of the track, combined with signals connected to said endless rod and operated by the operating 110 of the switch, substantially as set forth.

3. The combination of the endless rod or its described equivalent and a series of vertical levers flexibly connected in order to the upper and lower members of said rod, with a 115 switch mechanism comprising a switch-bar, a worm-geared segmental lever connected thereto, and a worm-shaft connected to and rotated by the movement of the said rod, the whole arranged parallel to the rails, substantially as 120 described.

4. A switch-operating mechanism comprising a switch-bar and rails, as usual, and two series of alternately rising and falling or reversing levers connected with the switch-bar, 125 and each by its operation in one way causing the other to operate in the reverse direction, thereby always to present for use one or the other series of levers, substantially as described.

5. A switch-bar and a locking mechanism connected therewith, which is also its operat-

ing medium, combined with series of rising and falling levers connected with said operating medium and arranged to work in series, so as to insure the presentation of one or the 5 other series in operative position for reversing the last movement of the switch, substantially as described.

In testimony whereof I have hereunto set my hand this 9th day of March, A. D. 1886.

A. INGRAM PARSONS.
